CLAIM

The ornamental design for a physical overlay sheet for forms, as shown and described.

DESCRIPTION

FIG. 1 is a front view of an example of the physical overlay sheet showing our new design;

FIG. 2 is a rear view thereof;

FIG. 3 is a side view thereof;

FIG. 4 is a front view thereof; the sheet in a first environmental use; and,

FIG. 5 is a front view thereof; the sheet in a second environmental use.

The drawings include broken lines that represent unclaimed subject matter only and form no part of the claimed design. The drawings include surface shading that represents contour and graphical symbols that represent transparent material. The surface shading and graphical symbols do not represent surface ornamentation.
